HEDDLE BAR SUPPORT

Charles E. A. Lausberg, Paterson, N. J.

Application December 14, 1943, Serial No. 514,294

2 Claims. (Cl. 139—92)

This invention relates to a support mechanism to be used for holding up the heddle bars in the heddle frames of looms.

By this invention I am able to make a heddle bar support which is simple and easy to operate but which holds the heddle bars firmly in place.

Broadly speaking, my invention comprises means for attaching the support to the heddle frame, a plate having a recess in the side to receive a heddle bar, a second plate pivoted on the first plate, also having a recess to register with the first recess and to close the same and spring-controlled detent means for holding the two plates superimposed to lock the heddle bar in place. If desired, the fixed plate can have a recess on each side and two pivoting plates can be supplied so that the device will support two heddle bars.

This invention may be readily understood by reference to the accompanying drawing, in which Fig. 1 shows a side view of the support mechanism, with the heddle frame and heddle bars shown in section; Fig. 2 is a section on line 2—2 of Fig. 1; Fig. 3 is a section on line 3—3 of Fig. 1; Fig. 4 is a side view of the support mechanism removed from the heddle frame and in open position to receive the heddle bars, with a portion broken away to show the detent construction; Fig. 5 is a side view of a device for holding a single heddle bar, and Fig. 6 is a view of the structure shown in Fig. 5 but taken at right angles and showing the device closed around a heddle bar.

In the drawing numeral 10 designates one of the rails of a heddle frame which is here shown as made of wood. Screwed into the frame member 10 is the pin 12 which carries a shoulder ring 14 and which, if desired, may be made integral with the screw 12. Also preferably integral with the screw 12 is a plate 16 having on each side a recess 18 shaped to receive a heddle bar 20. Pivoted on the respective sides of the plate 16 are the two plates 22 and 24 each of which has an enlarged recess 26 adapted to engage with a recess 18. Each of the plates 22 and 24 has at its free end a notch 28.

Passing through the plate 16 is a pin 30 which carries at each end a detent member 32. A spring 34 surrounds the member 12 and forces the detent members 32 away from the heddle frame. It will be noted that each of the detents 32 has a shoulder which, when such detent is engaged, overlies the outer face of the plate which it engages so that bending of such plate away from plate 16 is prevented. The detents thus lock the swinging plates firmly to the fixed plate as regards both swinging and bending.

The screw member 12 is screwed into the heddle support as shown in Fig. 2 and the plates 22 and 24 are swung down as indicated in Fig. 4. The heddle bars 20 are then located in the recesses 18 and the plates 22 and 24 are swung upwardly. Their curved corners will serve to lift the detent members 32 which will snap back into place in the recesses 28 when these plates are in position as shown in Fig. 1.

10 In the modification shown in Fig. 5, the plate 17 has a single recess 19 and carries a single pivoted plate 23 which has a notch 29 that cooperates with the detent member 33.

This device is extremely simple and can be 15 readily opened by simply lifting the detent device, but the heddle bars are firmly held in place and will not become loosened by twisting or other strains to which they may be subjected in use and the same mechanism which is used to lock 20 the heddle bars in place also serves to give added support to them during regular operations.

It is understood that the foregoing examples 25 are given by way of illustration in order that my device and the best way of utilizing the same may be readily understood, but it is not intended that the examples should serve by way of limitation, as various modifications thereof may be made without departing from the spirit of my invention.

30 What I claim is:

1. A heddle bar support comprising a plate, means for attaching said plate to a heddle frame in a plane transverse the line of the heddle bar, a recess in one side of the said plate adapted to 35 receive the heddle bar, a second plate pivoted in the first plate near the end farthest from the support-means, such second plate also having a recess to engage such heddle bar but with such recess opening in the reverse direction to the first 40 recess when the two plates are superimposed, a notch in the swinging end of such second plate, a detent slidably carried relative to said first plate and spring tensioned toward said notch, said detent having a portion to engage said notch 45 to hold said plate against pivoting and an overhanging shoulder to engage the outer face of the swinging plate when the device is closed.

2. A structure as specified in claim 1 in which the first plate has two recesses respectively opening on opposite edges and which includes two 50 pivotally mounted plates adapted to close such recesses and two detents to engage such plates, which detents are interconnected so as to be operated simultaneously.
